UNITED STATES PATENT OFFICE

SHIRO HIGUCHI, OF LOS ANGELES, CALIFORNIA

PROCESS OF TREATING BOILED BEANS

No Drawing.

Application filed March 14, 1930. Serial No. 435,967.

This invention relates to a new process of treating boiled beans, whereby the same are changed into a more nutritious and easily digestible food.

5 Heretofore and at present, boiled beans are consumed as food directly after the boiling thereof, or are kept in closed cans until used as food with no intervening steps between the boiling thereof and their final use as food.

10 To improve the boiled beans as an article of food, I subject them to a process as hereinafter set forth in detail and defined in the appended claims.

By subjecting boiled beans to my improved 15 process, they are changed chemically, thereby producing amide and peptone and making the beans nutritious and easily digestible; the amide element being derived from the skin or outer covering of the bean, and the peptone being derived from the albumen in the 20 inner bean kernel.

In carrying out my new process I have found that it is necessary to employ a number of small containers for the boiled beans, 25 and that these containers are most effective if made from a heavy paper fabric material, and in the form often used in paper cartons and known to the trade as "corrugated paper".

To carry out the process, I take beans, preferably soya beans, and add a quantity of water thereto, and boil the same at a temperature of 212° F., until the beans are well cooked. I then put the boiled beans in small 30 paper containers as above set forth, filling the containers about seventy-five per cent full, and then cover the containers, preferably with a paper fabric cover. I then arrange the containers side by side on sheets or blankets of heavy cloth fabric, and fold 35 the same to completely cover the containers.

I have found that a minimum of three sheets or blankets is desirable for this purpose. I then leave the enclosed containers in a closed 40 room having a temperature ranging from 80 to 90 degrees F., and for a period of thirty-six hours. I then take out the containers, and the contents are ready for use as food.

Through the use of heavy paper containers, and the wrapping of the same in three or 45 more heavy cloth fabric sheets or blankets,

and retention in a closed room having the temperature set forth, the heat in the boiled beans is gradually dissipated. During this step, a string-like gummy substance emanates from the beans and is deposited therebetween, 55 and consists mostly of amide, and a portion of the albumen within the bean kernels is changed into peptone; these chemical substances being developed only under the heat and conditions as attained by this process. 60

From the foregoing description, it may be seen that my new process develops in boiled beans, the desirable and nutritious substances of amide and peptone, and renders the boiled 65 beans very digestible.

What is claimed is:

1. The process of treating beans, consisting of boiling the same in water at a temperature of 212° F., until well cooked; then placing the boiled beans, while hot, in heavy 70 paper fabric containers including covers for the containers; then wrapping the containers in heavy sheets and blankets of cloth fabric; and finally in leaving the wrapped containers in a closed room having a temperature of from 80° to 90° F., for a period of 75 thirty-six hours.

2. The process of treating boiled beans, consisting of placing the boiled beans, while hot, in heavy paper fabric containers; then 80 wrapping the containers in sheets and blankets of heavy cloth fabric; then leaving the wrapped containers in a closed room having a temperature of from 80° to 90° F., and finally in removing the containers from the 85 heavy sheet and blanket wrappers.

3. The process of treating boiled beans, consisting of placing the boiled beans, while hot, in containers of heavy paper fabric; then 90 wrapping the containers in blankets of heavy cloth fabric; then in allowing the heat to dissipate therefrom in a closed room having a temperature of from 80° to 90° F., and finally in removing the containers from the 95 wrappers.

4. The process of treating boiled beans, consisting of placing the same, while warm, in containers which allow slow dissipation of heat; then in wrapping the containers in heavy blankets of cloth fabric which allow 100

slow dissipation of heat; then in leaving the wrapped containers in a closed room under a temperature of from 80 to 90 degrees, F., and for thirty-six hours, and finally in removing the containers from the wrappers.

5. The process of treating boiled beans, consisting of putting the boiled beans, while warm, in containers of heavy paper fabric, filling the containers about 75% full, the containers including a cover; then in wrapping the containers in heavy blankets of cloth fabric which allow slow dissipation of heat; then in placing the wrapped containers in a closed room having a temperature of from 80° to 90° F., for a period of thirty-six hours; and finally in removing the containers from the wrappers.

In testimony whereof, I hereunto affix my signature.

SHIRO HIGUCHI.
